UNITED STATES PATENT OFFICE

2,677,833

COMBINATION WARDROBE AND CRIB

Nathan J. Kroll, Chicago, Ill.

Application July 7, 1951, Serial No. 235,621

1 Claim. (Cl. 5—308)

1

This invention relates to a combination wardrobe and crib and has for its principal object the provision of a construction of the character hereinafter described which will be highly efficient in use and economical in manufacture. A principal object of this invention is to incorporate in a crib of a conventional construction such as that disclosed in United States Letters Patent No. 2,242,307, dated May 20, 1941, wardrobe drawers for the storage of bedding, clothing or other articles.

To accomplish this object it is contemplated that such wardrobe drawers be incorporated in the crib in a manner such that the crib may be sold with or without the wardrobe drawers thus leaving it optional to the buyer the desirability of having the drawers incorporated in the crib.

Another object of the invention is the provision of wardrobe drawers in a crib in a manner such that the drawer supporting structure will not interfere with the movable parts of the crib, such for example the side rails thereof.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a conventional crib with which my invention is associated;

Fig. 2 is a sectional detail view taken substantially on line 2—2 of Fig. 1;

Fig. 3 is a fragmentary perspective view of one corner of the panel illustrated in Fig. 2;

Fig. 3A is a fragmentary perspective view of another corner portion of the panel shown in Fig. 2;

Fig. 4 is a fragmentary sectional detail view taken substantially on line 4—4 of Fig. 2;

Fig. 5 is a fragmentary elevational view of a crib showing a modified form of construction of my invention associated therewith;

Fig. 6 is a fragmentary sectional detail view taken substantially on line 6—6 of Fig. 5;

Fig. 7 is a fragmentary perspective view of a corner portion of the drawer supporting panel shown in Fig. 6;

Fig. 8 is a fragmentary sectional detail view taken substantially on line 8—8 of Fig. 6, with a fragmentary sectional detail view of a drawer mounted on the drawer supporting panel shown in Fig. 6, and

Fig. 9 is a side elevational view of a supporting bar embodied in the invention and constituting a modified form of construction of the supporting bar illustrated in Figs. 3 and 7.

The several objects of my invention are preferably accomplished by the form of construction shown in the drawings in which drawings a crib is indicated at 10. This crib may be of any con-

ventional construction preferably similar to that shown in Letters Patent No. 2,242,307, and which as shown in such patent includes end panels 11 to which are slidably connected side rails 12. The end panels are connected together by a suitable spring structure 13 for the mattress 14.

It is in such a crib that I incorporate my improved wardrobe. In incorporating my improved wardrobe it is advisable from a sales viewpoint that the manner of incorporation be such that the crib 10 may be sold with or without the wardrobe feature. This leaves it optional to the purchaser as to whether it is desirable to have the combination crib and wardrobe.

It is also desirable from a manufacturing viewpoint that the wardrobe be such that it can be incorporated in the crib without the necessity of making any changes in the construction of the crib.

To accomplish these several objects of the invention, and addressing this specification to the preferred form of construction as shown in Figs. 1 to 4 inclusive, I provide a panel 15. This panel 15 is formed relatively light in weight. It comprises a frame 16 and thin panel sections 17. This panel 15 is of a size to fit between the side rails 11 in the manner shown in Fig. 2 and is detachably supported from the end posts 18 of these end panels in a substantially horizontal plane.

To accomplish this feature of the invention in each corresponding corner portion 19 of the panel 15, I connect by means of screws or bolts 20 to the end frames 20 of the panel 15 laterally extending supporting bars 21.

Each of these bars 21 is restrained from movement in the direction of the weight of the panel 15 thereon by means of pins 22 carried by the end frames 20 and projecting into notches 23 formed in the supporting bars 21 (see Fig. 3A).

The outer end portion of each supporting bar 21 is bifurcated as at 24 and in this bifurcated end portion is adapted to be received the shank of a head-bearing bolt or screw 25 carried by the adjacent end posts 18 of the side panels 11. By this construction when the panel 15 is mounted between the end panels 11 of the crib the supporting bars 21 are slidably positioned with respect to the bolts or screws 25 to project or locate the shanks of the latter in the bifurcated end portions 24 of the supporting bars.

The opposite corner portions 26 of the panel 15 are connected to the adjacent posts 18 of the end panels 11 by means of supporting bars 27 pivotally connected as at 28 to the end frames 20. The outer end portions of each of these bars 27, Fig. 3, is provided with a vertical notch 29 which is adapted to receive the shank of a screw or bolt 30 connected to the adjacent end post 18 of the crib 10.

Pivotal movement of these supporting bars 27

under weight of the panel 15 is limited by pins 30' carried by the end frame 20 and similar to the pins 22 and engageable in notches 31 similar to the notches 23.

To assemble the panel in the horizontal position shown in Fig. 2 the panel 15 is maneuvered so as to position the shanks of the bolts or screws 25 in the bifurcated ends 24 of the bars 21 after which the supporting bars 27 are hooked to the bolts or screws 30 thus completing a supporting connection between the panel 15 and the end panels 11.

The panel 15 is located just below the spring supporting the mattress 14. Extending transversely of the end frames 20 from the underside of the panel 15 are drawer supporting rails 32 having portions 33 thereof slidably operating in grooves 34 formed in the outer side walls 35 of suitable drawers 36. The adjacent side walls 37 of the drawers 36 are likewise supported from the panel 15 by means of drawer supporting rails 38 having portions 39 slidably operable in grooves 40 formed in such walls 37.

These drawers are provided with suitable handles 41. While I have shown two drawers beneath the panel 15, there may be provided a single drawer of a width such as will fit between the end panels 11 or if desired there may be three or more smaller drawers arranged beneath the panel 15.

By this arrangement as well as by the preferred form of construction to be presently described, the crib may be sold with or without the wardrobe. Also, the wardrobe may be sold for subsequent installation in a crib by the owner thereof. To accomplish this subsequent installation it requires only the proper location of the screws or bolts on the end panels 11 of the crib.

In the modified form of construction the drawers 42 (of which there may be one or more) are supported upon the panel 43 instead of below. The drawers 42 are carried in their slidable movement from and beneath the spring supported mattress 44 by guide rails 45 similar to the guide rails 32 and 38. Suitable covers (not shown) may be slidably associated with each drawer.

When the drawers are supported above the panel 43 such panel is removably supported in proper spaced relation with the spring supported mattress 44 by supporting arms 46 secured to and extending laterally from the corner portions 47 of the panel 43. These arms 46 are provided at their outer extremities with depending fingers 48.

The arms 46 are adapted to hook over the angle bars 49 connected to the posts 50 of the end panels 11' of the crib 10' and which angle bars 49 serve to connect the guide rods 51 to the end panels 11', the guide rods 51 providing a slidable connection between guide panels 11' and the side rails 12' of the crib in a manner disclosed in Patent No. 2,242,307. By this form of construction a very simple and inexpensive arrangement is provided by providing a detachable support for the wardrobe drawers.

Either form of construction may be manufactured at an economical cost and, as before stated, may be built in a crib at the factory or be furnished for installation in a conventional crib.

In Fig. 9, I have illustrated a supporting bar which has the combined features of the bar illustrated in Figs. 3 and 7. In this connection the bar is indicated at 52 and includes an elongated slot 53 through which the attaching screws 28 similar to the screws 28 are projected, the 75

elongated slot permitting the bar to be adjusted relative to the screw. In one edge of the bar is a rectangularly shaped notch 54 which is of a width and depth to receive the bar 49 attached to the post 50. In the opposite edge of the bar 52 is a notch 55 similar to the notch 54 and intended for the same purpose, namely, that of receiving the shank of the screws 30. When the bar 52 is used in the form of construction shown in Fig. 5, it is reversed so as to dispose the notch 54 at the bottom of the bar. When used in the form of construction shown in Fig. 2, the bar is attached to the end frames 20 in the position shown in Fig. 9. By this construction a bar is provided which may be used with the form of construction shown in either Fig. 2 or Fig. 5.

Also, if desired, the drawer 36 adjacent its bottom 26 may be provided with grooves 14' shown in dotted line. By this arrangement the drawer 20 may be used with either the form shown in Fig. 2 or with the form shown in Fig. 5.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A removable wardrobe for a bed having a mattress arranged between upright end members, said wardrobe comprising a relatively flat lightweight removable panel arranged in a substantially horizontal plane beneath and in spaced relation to the mattress and between the end members of said bed, said panel being of a size in plan view substantially the same as that of the adjacent surface of the mattress, means for detachably connecting said panel to said end members, said last-named means including bifurcated supporting bars pivotally carried by opposite corresponding corner portions of said panel and notch bearing bars pivotally carried by the other opposite corresponding corner portions of said panel, laterally extending shank bearing members carried by said end members and received in the bifurcations of said supporting bars and the notches of said notch bearing bars, stop pins carried by said corner portions adjacent said supporting bars and said notch bearing bars for limiting pivotal movement of the same when said shank bearing members are received therein, a drawer, means for slidably supporting said drawer from and beneath said panel, said panel constituting a cover for said drawer.
